Primary Examiner — Paula Allen Greene

(57) **CLAIM**

I claim the ornamental design for a supporting device for installing screen protectors on mobile telephones, as shown and described.

DESCRIPTION

1. Supporting device for installing screen protectors on mobile telephones
  4. Supporting device for installing screen protectors on mobile telephones
  5. Supporting device for installing screen protectors on mobile telephones
  6. Supporting device for installing screen protectors on mobile telephones
  7. Supporting device for installing screen protectors on mobile telephones
- 1.1:** Front Perspective
4.1: Front Perspective
5.1: Front Perspective
6.1: Front Perspective
7.1: Front Perspective

1 Claim, 5 Drawing Sheets
